GARMENT AND METHOD OF MAKING THE SAME

Herbert L. Miskend, New York, N. Y.

Application January 10, 1934, Serial No. 706,037

4 Claims. (Cl. 2—275)

My invention relates to a new and improved stitched garment and an improved method of making the same.

One of the objects of my invention is to provide an improved garment, such as an under-garment used for women's wear, which shall have a strong, flat, and non-rip seam.

Other objects of my invention will be set forth in the following description and drawing which illustrates a preferred embodiment thereof, it being understood that the above statements of the objects of my invention is intended to generally explain the same without limiting it in any manner.

15 Fig. 1 is an elevation of an improved garment.

Fig. 2 illustrates the first step in the formation of the junction or seam between two pieces of fabric which form a part of said garment.

Fig. 3 illustrates the next step in the formation 20 of the improved seam.

Fig. 4 illustrates the completion of the improved seam.

Figs. 2—4 inclusive are perspective views, partially in section.

25 As shown in Fig. 2, two pieces of fabric 1 and 2 have their edges 1a and 2a, connected by means of stitches 3 of any suitable type. These stitches 3 may be made by hand or by a suitable machine

if desired, although the ordinary hand stitch is 30 preferred in which the needle is alternately passed through the two edge portions 1a and 2a, from opposite sides thereof, so as to produce the ordinary running stitch. This stitch 3 can pull out very readily and stitching of this type is therefore 35 unsatisfactory.

As shown in Fig. 3, the next operation is to 40 form the ordinary French stitch, by means of a line of stitches 4. The pieces of fabric 1 and 2 now contact with their inturned edges 1a and 2a, the stitches 3 now being concealed.

It would not be departing from the invention if the stitches 4 passed through the inturned edge portions 1a and 2a as this would be an alternative 45 form of the invention. The stitches 4 may also be made by hand if desired.

The piece of fabric 1 is now bent outwardly, along the line of stitches 4, and the seam S is 50 now completed by an additional line of stitches 5 which can also be ordinary hand stitches. The completed seam has five layers of fabric. The stitches 3 are concealed, and the stitches 4 are also concealed on the right side of the garment, so that only the stitches 5 are visible.

55 The above mentioned construction provides a

strong and non-rip seam, with the use of a series of ordinary hand stitches.

It will be noted that two of the layers of fabric are secured by inwardly turning an edge of the member 2 and that three of said layers of fabric 60 are secured by turning the edges of the member 1 so as to secure an S-shaped fold.

I have shown a preferred embodiment of my invention, but it is clear that numerous changes and omissions can be made without departing 65 from its spirit.

I claim:

1. A garment having a first piece of fabric and a second piece of fabric, the first piece of fabric having its edge portion folded so as to produce 70 an S-fold which provides three superposed layers of fabric, the second piece of fabric having its edge inturned so as to provide two superposed layers of fabric, the inwardly turned edge portion of the second piece of fabric and the adjacent layer of the first piece of fabric being connected by means of transverse stitches which are invisible at the exterior of the seam, the second piece of fabric being also connected by means of 75 stitches to that portion of the first piece of fabric which directly abuts the body thereof, all the layers of fabric in said seam being connected by means of additional stitches.

2. A garment having a first piece of fabric and a second piece of fabric, the first piece of fabric having its edge portion folded so as to produce 80 an S-fold which provides three superposed layers of fabric, the second piece of fabric having its edge inturned so as to provide two superposed layers of fabric, the inwardly turned edge portion 85 of the second piece of fabric and the adjacent layer of the first piece of fabric being connected by means of transverse stitches which are invisible at the exterior of the seam, the second piece of fabric being also connected by means of stitches to that portion of the first piece of fabric which directly 90 abuts the body thereof, all the layers of fabric in said seam being connected by means of additional stitches, said stitches being arranged in series 95 which are laterally spaced from each other.

3. A garment having a first piece of fabric and a second piece of fabric, the first piece of fabric having its edge portion folded so as to produce 100 an S-fold which provides three superposed layers of fabric, the second piece of fabric having its edge inturned so as to provide two superposed layers of fabric, the inwardly turned edge portion of the second piece of fabric and the adjacent layer of the first piece of fabric being connected 105 by means of transverse stitches which are in- 110

- visible at the exterior of the seam, the second piece of fabric being also connected by means of stitches to that portion of the first piece of fabric which directly abuts the body thereof, all the 5 layers of fabric in said seam being connected by means of additional stitches, the second mentioned stitches skipping the inwardly turned edge of the second piece of fabric and the adjacent layer of the first piece of fabric.
- 10 4. A method of forming the seam in a garment which consists in stitching together the edge portions of a first piece of fabric and of a second piece

of fabric, turning the bodies of said pieces of fabric upon their edge portions and then connecting said pieces of fabric to each other by means of additional stitches, and then turning the first piece of fabric upon the last mentioned 80 stitches so as to form an S-shaped fold in the first piece of fabric, so that the two pieces of fabric have five layers of fabric, and then stitching said five layers of fabric to each other by means of additional stitches. 85
